UNITED STATES PATENT OFFICE.

MONTAGUE S. CHATTERTON, OF LONDON, ENGLAND.

DESIGN FOR A TABLET.

SPECIFICATION forming part of Design No. 33,846, dated January 8, 1901.

Application filed September 12, 1900. Serial No. 29,815. Term of patent 14 years.

To all whom it may concern:

Be it known that I, MONTAGUE SAXTON CHATTERTON, a subject of the Queen of Great Britain, residing at 132 Queen Victoria street, 5 London, England, have invented and produced a new and original Design for a Tablet, of which the following is a specification, reference being had to the accompanying drawings, forming part thereof.

Figure 1 is an elevation, and Fig. 2 an end view, showing my design.

As shown in the drawings, the leading or material feature of my design consists of a base part B, bent at a right angle to the main portion A, said base part B having downwardly-depending and inwardly-curved arms C C'.

The said tablet is particularly adapted for bearing advertising matter on the surface or surfaces thereof or may be used for ticketing 20 prices and such like on the articles to which it is adapted to be affixed.

Having described my invention, what I claim as new, and desire to secure by Letters Patent, is—

The design for a tablet as herein shown and described.

In testimony whereof I have signed my name to this specification in the presence of two subscribing witnesses.

M. S. CHATTERTON.

Witnesses:

H. I. HADDAN,
A. E. MELHUISH.
